[57] CLAIM

The ornamental design for a combined thermometer
and a holder for a calendar and a ball point pen, as
shown and described.

DESCRIPTION

FIG. 1 is a front elevational view of a combined ther-
mometer and holder for a calendar and a ball point pen
showing my new design;

FIG. 2 is a rear elevational view;

FIG. 3 is a top plan view;

FIG. 4 is a bottom plan view;

FIG. 5 is a right side elevational view; and

FIG. 6 is a left side elevational view.
The indicia shown on the thermometer in FIGS. 1 and
3 is for illustrative purposes only.

FIG. 2
